UNITED STATES PATENT OFFICE.

PETER A. ARONSON, OF BRIDGEPORT, CONNECTICUT, ASSIGNOR TO HOOKLESS FASTENER COMPANY, OF MEADVILLE, PENNSYLVANIA, A CORPORATION OF PENNSYLVANIA.

SEPARABLE FASTENER.

Application filed June 14, 1923. Serial No. 645,223.

This invention relates to separable fasteners of the slider controlled type, and has for its objects to provide a novel construction of interlocking recesses and projections whereby to increase flexibility and reduce friction; also to enable such members to be made of flat strip material; and more specifically to construct such members of flat strip material bent so as to require a minimum number per unit of length of tape with improved holding power.

In the recess and projection type of interlocking members disclosed herein, flexibility is increased and friction decreased by causing one to make a line or spot contact with the other, as distinguished from a surface to surface contact. This is attained by a novel interlocking member having a projection on one side and a projection receiving recess on the opposite side, the sides of the projection and of the recess being relatively inclined so that in locking and unlocking, and when engaged, an edge or spot of one engages a surface of the other. This construction is conducive to lateral flexibility because the relative inclination provides the required facility of movement and prevents disengagement. When members of this type are subjected to transverse strain when engaged, the relative inclination tends to make one ride on the other and thus cumulatively increase the holding power.

In the several forms of invention shown herein, for purposes of illustration, the interlocking members are made from successive pieces of wire of generally flattened cross section by being cut off to the desired length, then bent up after being stamped or perforated to provide a shell type of member each comprising separated pairs of compressible jaws for clamping to a tape, an oppositely disposed recess and projection, a bridging element connecting the spaced pairs of jaws, and slider guiding means parallel with the tape and forming a track on which the slider moves. The number of interlocking members per unit length of tape may be varied by varying the length of the bridging element. The invention in its broad aspects, however, is not limited to shell type interlocking members.

It is important in this type of fastener that the locking members be clamped se-

curely on the tape so as not to slip longitudinally or transversely and yet they must not be clamped so tightly as to cut either the cord or tape. The corded edge of the tape is compressed or flattened by the compression of the jaws which causes the cord to bulge on either side. In this invention by having each locking member held in place by two pairs of spaced clamping jaws, the relative swelling of the tape within the locking member and between these spaced jaws is effective in holding the members securely in position. With such an arrangement the clamping force may be distributed between the two pairs of jaws requiring less clamping action in each pair whereby likelihood of cutting is lessened, as well as the danger of the tape not lying flat.

Referring to the drawing:

Figure 1 shows one embodiment of my invention in a partially closed fastener,

Fig. 2 is an enlarged detail of one of the locking members shown in Fig. 1,

Fig. 3 is a section on the line 3-3 of Fig. 2,

Fig. 4 is an enlarged detail of another form of locking member,

Fig. 5 is a section on the line 5-5 of Fig. 4,

Fig. 6 is a developed plan view of the locking member shown in Fig. 2 before being bent to the shape illustrated,

Fig. 7 is a transverse section illustrating one form of fastener when transversely flexed,

Fig. 8 is a transverse section illustrating the co-operation between locking members of the form shown in Fig. 3 when the fastener is flexed,

Fig. 9 is a top plan view showing the locking member of Fig. 2 clamped in position on a tape,

Fig. 10 is a transverse section through a locking member similar to the ones illustrated in Fig. 7, and

Fig. 11 is a transverse section of another form of locking member in which both the top and bottom surfaces are rounded.

Referring to the drawings, the stringers 10, preferably of woven tape, for example, have sewed thereto on opposite sides braided or twisted cords 11 to form a beaded edge 105 to which are secured a plurality of locking

members 12 alternately arranged on the tape and adapted to be controlled by the slider 13. Each member 12 is formed from a piece of flat wire or strip metal bent back on itself in a general U, hollow shell or rectangular shape provided with locking portions comprising an interlocking projection 14 stamped on one side and a recess 15 on the opposite side with which the adjacent locking members cooperate. The projection 14 and recess 15 are in substantial alignment and are set in from the edges of the member 12. The flat wire blank from which these members are formed has substantially parallel longitudinal edges and jaws 16 and 17 formed by stamping out the metal occupied by a cross section of the corded tape of the stringer, spreading the jaws as shown in Fig. 6 in order to receive the edge of the tape, and then clamping the jaws to the stringer by compression as shown in Fig. 9, for example. The jaws 16 and 17 are connected by an integral bridging element, as shown in Figs. 1, 2 and 4. The corded edge 25 of the stringers is spaced from the locking members by the portions 16' and 17'. The end portions of the jaw members are extended and bent to lie along the stringer, as shown in Figs. 1, 2 and 4, where these end portions 18 and 19 are bent in the same direction to provide a track along which the slider travels. According to this invention the sides of the interlocking projections 14 and recesses 15 are relatively inclined, that is, one is inclined with respect to the other, to permit only an edge or spot of one to engage a surface of the other in locking and unlocking and in lateral flexing. In the modifications illustrated, for example, the 40 sides of the projections 14 are inclined and the sides of recesses 15 are substantially vertical or straight. In Figs. 3 and 5, the projection 14 is transversely elongated, flat and tapered, while in Figs. 10 and 11 the projection 14 is transversely rounded or substantially hemispherical. In some forms of the invention the recess 15 is substantially wider transversely than the projection 14 as shown, for example, in Figs. 3 and 5, 45 while in other forms, shown in Figs. 10 and 11, the recess is not substantially wider transversely than the projection but is merely large enough to fit over the projection. By making the recesses substantially wider 55 transversely than the projections the projections can move easily inside the recesses when interlocked and flexed.

When the closed fastener is flexed transversely, as shown in Figs. 7 and 8, an edge 60 of the recess 15 slides or pivots on the surface of the projection 14 of a cooperating member or vice versa. In locking and unlocking, as well as in lateral flexing, one interlocking portion makes only a line or 65 spot contact with the other. Since only rel-

atively small portions of the cooperating projections and recesses contact at any time, the friction between them is greatly reduced, flexibility is increased, and ease in locking and unlocking is promoted. Against transverse strain when the interlocking members are engaged, the relative inclination of engaging surfaces has another function. This is to enable these members to ride easily on one another and thus cumulatively increase 75 the locking effect due to the inability of the members to separate longitudinally at their rear ends where attached to the stringer. The strain at the back due to the riding at the front is taken up by slight tension on 80 the tape between the members.

In order to permit the fastener to flex in closed position the surface around either the projection or recess, or both may be transversely rounded to permit one locking member 85 to rock on its oppositely adjacent cooperating member, as shown in Figs. 7 and 8. In Figs. 2 and 3 both the surfaces 20 and 21 around the projection and recess are rounded transversely, one being concave 90 and the other convex. In Figs. 4, 5 and 10 only one such surface 22 or 24 is rounded while the other surface 23 or 25 is substantially flat. In Fig. 11 both the surfaces 24 and 25 are transversely convexed to facilitate flexure.

Among the advantages of this invention may be mentioned the novel construction of interlocking recesses and projections which reduces friction and increases flexibility and ease of locking and unlocking. Another advantage lies in the construction whereby the cooperating locking members rock on the surfaces surrounding the recesses and projections instead of directly on the surfaces 100 of the projections and recesses themselves. Another advantage resides in the simplicity of construction whereby a fastener member is stamped from a flat wire and bent to the desired shape without the previously necessary finishing operations inasmuch as the sides of the wire form the side faces of the jaw members. The number of locking members per unit length of stringer may be varied by controlling the length of the 105 bridging element. The use of spaced clamping jaws provides a double grip on the tape and lessens the liability of the locking member slipping along the tape and the space between the pairs of clamping jaws provides 115 a suitable location for a bulge in the corded edge which is caused by the clamping action of the jaws and is helpful to retain the locking member in place. The formation of the jaws is accomplished with a minimum 120 waste of material. Reduced friction and longer life for the slider are some of the advantages resulting from the increased metal track or slider guiding means formed by bending the ends of the locking strips to 125 130

lie parallel with the tape edge. With the double grip upon the tape less clamping action in each pair of jaws is necessary in order to prevent the locking member from moving longitudinally on the tape. In this invention where the locking members are of the hollow type it might be desirable to use one or more overlapping flaps, for example, as illustrated in Fig. 5 of the patent to Sundback, #1,432,219, dated October 17, 1922, to prevent granular or other material, from passing through the locking members and leaking out of the container, or whatever the fastener is applied to.

18 The invention is not limited to the particular modifications herein shown and described. The novel cooperating recesses and projections may be employed in various types of interlocking members. Various 20 other changes may also be made in the details of construction without departing from the scope and spirit of the invention as defined in the appended claims.

I claim:

25 1. An interlocking member for a separable fastener stringer composed of flat material formed with compressible jaws to engage a stringer, having on one face an engaging projection and on the opposite face in alignment therewith a larger projection receiving recess, the sides of the projection and recess being relatively inclined.

2. A locking member for a slide type fastener comprising a strip of material shaped 30 to provide a pair of clamping jaws and having a recess and projection one above the other in substantial alignment, said recess being transversely wider than the projection an amount sufficient to permit the projection 40 of a similar locking member to rock transversely therein.

3. A sheet metal locking member for a separable fastener comprising clamping jaws for attachment to a tape, a projection 45 on one side, well in from the edges thereof, an aligned recess on the opposite side of said member also spaced from the side edges and substantially wider transversely than said projection to permit rocking of the projection of a similar locking member therein.

50 4. In a slide actuated fastener, cooperating interlocking members composed of flat material each having a projection on one side and a projection receiving recess on the opposite side, the sides of each projection and the recess with which it cooperates being relatively inclined a substantial amount sufficient to cause an edge of one to engage a surface of the other when interlocked.

55 5. A separable fastener comprising a pair of stringers having interlocking members composed of flat material each provided with a projection on one side and a recess on the opposite side well in from the edges thereof, the sides of each projection and the

recess with which it cooperates being relatively inclined to permit an edge of one to engage a surface of the other without separating when interlocked.

6. A separable fastener comprising a pair 70 of stringers having interlocking members composed of flat material each provided on one side with a projection and on the opposite side with a larger projection receiving recess, the sides of said projection and recess being non-parallel to provide a line or spot contact between the projection and a cooperating recess when brought together.

7. A separable fastener comprising a pair 80 of stringers having interlocking members composed of flat material with a portion cut out to provide clamping jaws, each of said members being provided with aligned interlocking portions one of which is inclined and the other of which is substantially straight 85 for rocking engagement with cooperating interlocking members.

8. In a separable fastener, a pair of stringers having interlocking members composed of flat material with a portion cut out 90 to provide clamping jaws, each of said members being provided with a substantially straight interlocking portion and another aligned interlocking portion which is inclined sufficiently to cause it to pivot on an 95 edge of the straight interlocking portion of a cooperating interlocking member.

9. A locking member for a separable fastener comprising means for securing the same to a tape, an inclined projection on one 100 side of said member, and a larger projection receiving recess having substantially vertical walls on the opposite side of said member in substantial alignment with said projection.

10. A separable fastener comprising a pair 105 of stringers provided with similar cooperating interlocking members each having a projection struck up on one side and a larger projection receiving recess formed on the opposite side in substantial alignment with 110 said projection, the sides of said projection and recess being non-parallel and proportioned to permit said projection to contact with only a portion of the recess with which it cooperates.

11. A separable fastener comprising a pair 115 of stringers provided with similar cooperating interlocking members each having a projection struck up on one side and a larger projection receiving recess formed on the opposite side in substantial alignment with said projection, the sides of said projection and recess being relatively inclined and proportioned to permit said projection to lie in the recess of a cooperating interlocking member with the greater part of said projection out of contact with the sides of said recess.

12. In a slide actuated fastener, cooperating interlocking members composed of flat 120

125

- material each having a projection on one side and a projection receiving recess on the opposite side well in from the edges thereof, the sides of each projection and the recess 5 with which it cooperates being relatively inclined to permit an edge of one to pivot on a surface of the other without separating under strain, and the surfaces of said members around each projection and its cooperating recess being relatively relieved to facilitate engagement when separated.
13. A separable fastener comprising a pair of stringers having interlocking members composed of flat material each provided with 15 transversely elongated interlocking portions on opposite sides of the member, the sides of one interlocking portion of each member being inclined with respect to the sides of the other interlocking portion thereof to provide 20 a line or spot contact between cooperating interlocking members.
14. A separable fastener comprising a pair of flexible stringers each carrying a series of spaced locking members, a locking member 25 of one series cooperating with a locking member of the opposite series to form an interlocking pair, each locking member of each series being provided with means for rigidly attaching it to the edge of its 30 stringer and having a free end adapted to overlap the free end of the other locking member of the interlocking pair, a projection adjacent the free end of each locking member, and a recess adjacent the free end 35 of each locking member in alignment with the projection thereof and substantially larger than said projection to receive the projection of the other locking member of the interlocking pair, the recess and projection 40 of each interlocking pair being relatively inclined to permit an edge of one to engage a surface of the other in locking and unlocking and in lateral flexing.
15. A locking member for a separable fastener comprising means for securing the same to a tape, a projection set transversely inward of the edges of said member, the surface of said member transversely on each side of said projection sloping slightly away 45 from said projection.
16. A locking member for a separable fastener comprising means for securing the same to a tape, a projection set inwardly from all edges of said member, the surface 55 of said member around said projection being transversely rounded to raise the height of the surface around said projection above the side edges of said member.
17. A sheet metal locking member for a 60 separable fastener comprising clamping jaws for attachment to a tape, a projection on one side, well in from the edges thereof, an aligned recess on the opposite side of said member also spaced from the side edges and substantially wider transversely than said 65 projection to permit rocking of the projection of another locking member therein, the surface between said projection and the side edges of said member sloping gradually away from said projection. 70
18. A locking member for a slide type fastener having means for securing the same to a flexible stringer, an interlocking portion, and a surface adjacent said interlocking portion extending away from said flexible 75 stringer and rounded transversely to facilitate transverse rocking on a continuous locking member.
19. A separable fastener comprising a pair of stringers having corded edges, and a plurality of interlocking members mounted on 80 said stringers and each having an elongated end the major portion of which is adapted to contact with the corded edge of the opposite stringer to restrain said interlocking members against pivoting on each other out of the plane of said stringers when the fastener is closed. 85
20. A separable fastener comprising a pair of stringers having cooperating interlocking members composed of flat material having 90 an interlocking portion set inwardly from the edges thereof, and a sloping surface adjacent and surrounding said interlocking portion on at least two sides thereof to facilitate sliding on a cooperating interlocking member. 95
21. A separable fastener locking member comprising a flat strip of material transversely bent in the middle having ends provided with compressible clamping jaws and having a projection adjacent the bend on one side and a recess adjacent the bend on the other side. 100
22. A separable fastener locking member comprising a flat strip of material bent double having parallel ends provided with compressible clamping jaws and having a projection adjacent the bend on one side and a recess adjacent the bend on the other side. 105
23. A locking member for a slide type fastener comprising a strip of material shaped to provide pairs of clamping jaws, a projection adjacent one pair of jaws, a recess adjacent the other pair and a bridging element connecting said pairs. 115
24. A locking member for a slide type fastener comprising a strip of material shaped to provide spaced pairs of jaws for clamping the member to a tape, a projection adjacent one pair and a recess adjacent the other pair, a bridging element connecting said pairs, and slider guiding means bent to lie substantially parallel with the edge of said tape. 120
25. A locking member for a slide type fastener provided with an interlocking recess and projection and spaced tape gripping portions having an intervening recess between them longitudinally of the tape to 125

- permit a bulge in the tape in said recess between said gripping portions.
26. A locking member for a slide type fastener provided with compressible jaws adapted to be secured to a tape and having the ends of said jaws extended and bent to lie along the tape in a direction substantially parallel to its edge and between adjacent locking members on said tape to stiffen the same.
27. A locking member for a slide type fastener formed of a strip of material bent to form spaced portions and having a projection in one portion, a recess in another portion of said strip spaced from said projection, and tape gripping means in yet another portion of said strip.
28. A hollow shell locking member for a slide type fastener comprising a strip of metal bent to form parallel sides, a projection on one side, a recess on the opposite side separate from said projection, and means for securing said member to a tape.
29. A locking member for a slide type fastener shaped to provide a projection and recess spaced transversely from the edges of said member, and means for clamping said member to a tape, the surfaces around the recess and projection being at least one of them transversely sloping slightly downwardly from said projection to facilitate rocking of one locking member on an opposite adjacent locking member when the fastener is flexed.
30. A locking member for a slide type fastener shaped to provide a projection and recess, and means for clamping said member to a tape, the surfaces around the recess and projection being one of them transversely rounded to facilitate rocking of one locking member on an opposite adjacent locking member when the fastener is flexed.
31. A locking member for a slide type fastener provided with compressible jaws adapted to be secured to a stringer, a projection and recess opposite said jaws, the surfaces of said member around said projection and recess being at least one of them transversely and convexly rounded to permit rocking of one locking member on an opposite adjacent locking member when the fastener is flexed.
32. A locking member for a slide type fastener comprising a strip of material bent to provide pairs of jaws for clamping the member to a tape, a recess adjacent one pair and a projection adjacent the other pair, a bridging element connecting said pairs of jaws and located between the recess and projection, and slider guiding means formed by bending an end portion of said strip to lie along the tape substantially parallel to its edge.
33. A locking member for a slide type fastener provided with compressible jaws adapted to be secured to a tape and having an end of each of said jaws extended and bent to lie along the tape in a direction substantially parallel to its edge and between adjacent locking members on said tape to stiffen the same.
34. A locking member for a slide type fastener comprising spaced pairs of clamping jaws, a bridging element connecting said pairs of jaws, and an interlocking part stamped from the material of said locking member outwardly of said pairs of jaws.
35. A locking member for a slide type fastener comprising a transversely bent sheet metal strip shaped to provide spaced pairs of clamping jaws, a bridging element connecting said jaws, a projection bent up from the material of said member spaced outwardly from said pairs of jaws, and means to receive a projection of a co-operating locking member.
36. A locking member for a slide type fastener bent to provide a projection and having a recess, means for clamping said member on a tape, the surface around both the projection and recess being transversely rounded to facilitate rocking of one locking member on an opposite adjacent locking member when the fastener is flexed.
37. A locking member for a slide type fastener shaped to provide a projection and recess, means for clamping said member on a tape, the surfaces around the projection and recess being at least one of them transversely and convexly rounded while the surface around the other is transversely concaved to facilitate rocking of one locking member on an opposite adjacent locking member when the fastener is flexed.
38. A locking member for a slide type fastener comprising a strip of material bent to provide pairs of clamping jaws, a recess adjacent one and a projection adjacent the other pair of jaws, and a bridging element connecting said pairs of jaws, the projection being rounded and the recess being stamped out and having walls substantially transverse to the plane of the jaws.
39. A locking member for a slide type fastener comprising a flat strip of material having two spaced pairs of compressible jaw members adapted to be clamped to a tape, said strip being bent transversely to provide a bridging element connecting said jaws and provided with a projection adjacent one pair, a recess adjacent the other pair and another portion of the strip being bent normal to the plane of the jaws to provide slider guiding means lying along the tape and extending toward an adjacent locking member to stiffen the tape.
40. A locking member for a slide type fastener comprising a strip of material bent to provide pairs of jaws for clamping the member to a tape, a recess adjacent one pair and a projection adjacent the other pair and a bridging element connecting said pairs of jaws.

jaws and located between the recess and projection with said pairs of jaws in the end portions of the strip.

41. A locking member for a slide type fastener comprising a sheet metal strip bent back on itself, compressible jaws for attachment to a tape having a corded edge, said locking member being relatively long in the direction of said tape, at least one of said jaws being bent to provide a track substan-

tially parallel to the corded edge of the tape and along which a slider may travel, an interlocking part located outwardly of said jaws, and means between said interlocking part and jaws for spacing the corded edge ¹⁵ of the tape from said interlocking part.

Signed at Bridgeport in the county of Fairfield and State of Connecticut, this 9th day of June, A. D. 1923.

PETER A. ARONSON.
